HENRY H. WHEELER, OF BROOKLYN, NEW YORK, ASSIGNOR TO INTERNATIONAL CIGAR MACHINERY COMPANY, A CORPORATION OF NEW JERSEY

CIGAR ENVELOPING MACHINE

Application filed July 2, 1927. Serial No. 203,082.

This invention relates to an improvement in a cigar enveloping machine, its main object being to produce a machine which wraps tin-foil or other enveloping material around completed cigars and which neatly folds the ends of such envelopes automatically at high speed. Generally speaking, the cigars to be wrapped are deposited on a conveyor which intermittently feeds them into the range of action of a plunger which transfers them with their envelopes into one of the assemblage receivers of an intermittently rotating turret having separated assembling and sealing and discharging stations. The envelop material is fed downwardly from a reel across the front of a receiver while the latter is in horizontal position at assembling station. In entering the receiver, the cigar pushes the envelop ahead of it, thereby folding the envelop around three sides of the cigar. The envelop is automatically cut from a strip to the proper length as soon as the advancing cigar holds it against a yielding base of the receiver that is provided for this purpose in each turret arm. A movable folder which is brought up from below the receiver then folds the underlapped edge of the envelop up under the upper flap and against or on the cigar. The overlapped edge is subsequently folded down and held in position by a stationary folder attached to the frame of the machine as the receiver moves along said folder from horizontal position at the assembling station to vertical position at the sealing station.

When the envelop arrives at the uppermost position of the receiver at the sealing station, it tightly envelops the cigar and is sealed by closing its ends. A preliminary folder consisting of a male and female die is first closed over each envelop end, thereby pressing the ends into channel form. A split cup mounted on a hollow shaft coaxial with the cigar is then pushed against each end, these cups being so shaped that in engaging the envelop, one upstanding side of each channel end is folded down on the cigar, while the other enters the slot of the cup in upstanding position. While the cigar remains stationary at the sealing station, the cups are turned

through one revolution, thereby laying the upstanding sides of the envelop ends down on the previously folded sides of the same. The cups then dwell long enough to permit knife-edged tuckers to move down into transverse slots in the cups to form tucks at the ends of the envelops. Upon raising the tuckers, the axial plungers are advanced to their innermost position, thereby folding the tucks formed in the envelop closely against the cigar. Thereupon, the cups are again turned through one revolution, during which a suitably shaped surface on each cup smooths the points and seals the envelop tightly to the cigar.

The envelop being thus properly applied to the cigar, the turret advances one step, or a quarter of a revolution, and brings the arm holding the enveloped cigar into horizontal position at the discharging station diagonally opposite to the receiving or assembling station.

Arrived at the discharging station, clamps in the receiver are automatically opened, permitting the released cigar to be pushed into the carrier by an ejector on the turret arm, a pair of cam-actuated ejecting fingers being provided to perform this function in case the yielding base of the receiver should fail to operate promptly, or in case the cigar should stick to the receiver, and also to act as a guard to prevent the cigar from falling out of the carrier during transit. The carrier then swings through an arc of 90 degrees and deposits the enveloped cigar upon a delivery table, the cigar having made a quarter of a revolution just before assembly with its envelop, a half of a revolution while in the turret, and another quarter of a revolution while in the carrier. As the cigars are ejected in the same order in which they are fed into the machine, they therefore can, if enveloped after being packed in the box, be replaced in the same order and in the same relative position as when taken out of the box. With the major object of producing a machine of the general character above described and with minor objects not specifically mentioned in view, the invention consists in certain constructions and combinations which will be

hereinafter fully described and then specifically set forth in the claims hereunto appended.

In the accompanying drawings, in which like characters of reference indicate the same or like parts, Fig. 1 is an end elevation of a machine constructed in accordance with the invention, some of its parts being broken away to show details of construction; Fig. 10 1^a is an end elevation of a part broken away from Fig. 1; Fig. 2 is a sectional side elevation of the machine shown in Fig. 1; Fig. 3 is a plan view showing the mechanism of the machine of Figs. 1 and 2 for folding the ends 15 of the envelops on the cigars; Figs. 4 and 5 are respectively end elevation and sectional views of the means employed for giving channel form to the ends of the envelops as a preliminary folding operation; Figs. 6, 7 20 and 8 are respectively side elevation, end view, and top and plan view of the split cups employed in the envelop folding operation; and Figs. 9 to 16 inclusive are perspective views showing the various stages of the envelop end folding operation.

In carrying the invention into effect, there is provided a traveling assemblage receiver having separated assembling, sealing and discharging stations, means for assembling a 30 cigar and an envelop in said receiver, means for partially enveloping the cigar at the assembling station, means for completing envelopment of the cigar between the assembling and sealing stations, means for closing 35 by different folds the ends of the envelop at the sealing station, and means for discharging the sealed cigar at the discharging station. In the best constructions contemplated, there is further provided means for feeding 40 box rows of cigars to the assembling station; the assembling means includes means for turning the cigar 90 degrees in moving it with its envelop into the receiver at the assembling station; the partially enveloping 45 means includes means for folding the underlap edge of the envelop on the cigar in the receiver at the assembling station; the completing means includes means for folding the overlap edge of the envelop of the cigar between the assembling and sealing stations; the closing means includes cooperative oscillatory and rotatory and reciprocatory folding devices simultaneously operating on both 55 ends of the envelop at the sealing station; the discharging means includes means for turning the cigar 90 degrees while discharging it from said receiver at the discharging station; and a series of traveling assemblage receivers are employed. The above mentioned 60 means and parts may be widely varied in construction within the scope of the claims, for the specific machine selected to illustrate the invention is but one of many possible concrete embodiments of the same. 65 The invention therefore is not to be restricted

to the precise details of the structure shown and described.

Referring to Figs. 1, 2 and 3: The frame 20 of the machine is mounted on a bed 21 supported by legs 22 joined by a brace 23. It 70 carries a clutch shaft 24, a cam shaft 25, a turret shaft 26, conveyor shafts 28 and 29, fulcrum shafts 30, 31, 32, 33, 34, 35, 36, 37 and 38, feed roller shafts 39 and 40, brackets 41 and stands 42.

The shaft 24 carries a clutch 43 actuated by a belt 44 deriving its motion from any suitable source of power, and by means of a pinion 45 meshing with a gear 46, drives the cam shaft 25. The latter has a spur gear 47 meshing with a gear 48 on the turret shaft 26. The brackets 41 support the hollow shafts 49 on which the envelop folders 50 are mounted and in which folding plungers 51 slide. They also support other parts of the end folding device. The stands 42 are braced by a tie rod 52 and serve as supports for the reel shaft 53.

The cigars 54 to be enveloped are placed in a row of 12 or 13 cigars, as required for boxing, or in a row of any other number if desired, upon the feed table 55, a hinged guard plate 56 keeping the row in a continuous line while being inserted and advanced. Two conveyor chains 57, spaced apart about one-half a cigar length and running over sprockets 58 and 59 on the shafts 28 and 29' respectively, by means of the driving pin 60, advance the cigars in a step by step movement imparted to the shaft 28 by a ratchet 61 operated by a pawl 62 on an arm 63 held in rearward tension by a spring 64 and actuated in the forward direction by a rod 65 controlled by an arm 66 of a 3-armed lever fulcrumed on the shaft 32 and engaging, by means of a roller 67 on an arm 68, the track of a cam 69 on the shaft 25. In order to allow for the difference in the length of the rows as between 12 and 13 cigars and also other cigars of different thickness, a bar 70 having an upwardly approaching finger 71 midway between the two conveyor chains 57 is pivoted to a sleeve on the shaft 28 by a crank 72, and to the shaft 29' by an arm 73, the shaft 29' being connected with the shaft 28 by cranks and connecting rod. By this arrangement, the finger 71 in contact with the first cigar in the row at each back stroke of the pawl 62, will control each forward step of the conveyor.

A cigar having arrived at the end of the table 55, a plunger 74 operated by the shaft 31 raises the cigar on the curved guide 75 and delivers it to the turret. The shaft 31 has a pinion 76 meshing with a gear segment 77 pivoted on the shaft 30, this segment forming one arm of a bell crank lever, the other arm 78 of which carries a roller 79 engaging the cam 69 on the shaft 25. The plunger 74 has curved downwardly projecting tails 130

80 which close the space between its forward edge during its upward movement, and thus prevent the cigars from rolling into the path of the plunger after it has left its cigar receiving position.

On its way to the turret, the cigar ahead of the plunger 74 encounters the envelop strip 81 which hangs down from between rollers 82 and 83 on the shafts 39 and 40 respectively, and is held by guides 84 in close proximity to the turret and across the front of the assemblage receiver. As the cigar passes into the receiver, which is formed by a stationary clamp 85, a movable clamp 86 and a yielding base 87, the envelop is cut by a knife 88 and is pushed by the advancing cigar into the receiver between the clamps 85 and 86 and against the yielding base 87.

20 The envelop strip 81 is fed to the rollers 82 and 83 from a reel 89 on the shaft 53, the lateral position of the reel being adjustable by means of a screw 90. Unwinding of the envelop strip during the cutting period when 25 the rollers 82 and 83 are at rest is prevented by a weight 91 suspended from the rod 51 by a strip 92 which rests on the envelop roll and acts as a brake. The feed rollers are actuated by a chain 93 driven from a sprocket 94 on the turret sleeve of the shaft 26, the driven sprocket 95 being mounted on an adjustable arm 96 clamped on a stationary bushing of the turret shaft sleeve. The sprocket 95 drives the gear 97 which is in mesh with the gear 98 on the shaft 39. The spring 99 holds the feed roller 82 against the roller 83 and is made adjustable by means of a screw 100.

40 The envelop strip cutter 88 is mounted on a vertical shaft 101 (Figs. 1 and 3) and is controlled by a lever 102 engaging the track of a cam 103 on the shaft 26 by means of a roller 104.

45 The rigid arms of the turret which are integral with the clamps 85 are also integral with its hub which is mounted on a sleeve 105 surrounding the central portion of the shaft 26. Each of these arms carries a yielding base 87 for the receiver provided with 50 guide pins 106 which are slidable in radial holes drilled in the arms 85 for this purpose, the yielding bases 87 being pressed radially outward by springs 107 housed in the arms 85 and bearing against the studs 108 attached to said yielding bases. The movable clamps 86 are in the form of bell crank levers pivoted in the head of the turret and having arms 109 and 110 on either side of the rigid clamps. 55 The arms 109 on one side are interconnected by springs 111, while the arms 110 on the other side carry rollers 112 engaging the perimeter of an oscillating cam 113 mounted on the turret shaft 26. The cam 113 is controlled by a lever 114 clamped to its hub and

engaging a cam 115 on the shaft 25 by means of a roller 116.

The turret is driven intermittently by a Geneva gear 117 on the sleeve 105, the gear 117 being actuated by a roller 118 carried by a cam 119 on the shaft 25. It turns the turret a quarter of a revolution for every complete revolution of the shaft 25.

70 When the cigar 54 has entered the turret clamps, with the cut envelop 120 partially enveloping the cigar, the underlap edge of the envelop which is hanging down between the guides 84, is folded against or on the cigar by a folder 121 which is mounted on a vertical block 122 carried between levers 123 fulcrumed on the shaft 34 and levers 124 fulcrumed on the shaft 35 and actuated by a roller 125 mounted on one of the levers 124 and engaging the cam 119 on the shaft 25. 75 Then the turret turns a quarter of a revolution and advances the cigar 54 into the envelop end sealing position at the highest point of the turret which is the sealing station.

80 On rising with the turret arm, the overlap edge of the envelop 120 is folded down over the underlap edge of the same by a stationary folder 126 between the assembling and sealing stations and is held by said folder in position during the subsequent end folding operations.

85 The cigar 54 having arrived at the sealing station at the top of the turret, with an envelop neatly wrapped around it, the enveloping operation is continued by sealing the ends of the wrapper. With this end in view, the 90 ends are first subjected to the action of a preliminary folder consisting of complementary dies 127 and 128 (Figs. 4 and 5) which are pressed together on the ends of the envelop (as shown in Fig. 9), and thereby give to them the channel form 129 (shown in Fig. 10). The upper or male dies 127 are attached to an oscillatory frame 130, and the lower or female dies 128 are attached to an oscillatory frame 131, both frames being mounted on the 95 shaft 37, the former loosely and the latter fixedly. The frames 130 and 131 are actuated by a bell crank 132 fulcrumed on the shaft 32 and having a roller 133 in engagement with a cam track in the gear 46 on the shaft 25, its other arm engaging—by a pin 134—the slotted end of a lever 135 fulcrumed on the shaft 37. Upon the shaft 37 is fixed a gear segment 136 in mesh with a gear segment 137 on the shaft 38 to which is attached a lever 138 connected by a link 139 with the frame 130. Thus, the rocking motion imparted to the shaft 37 by the cam 46 closes and opens the preliminary folding dies 127 and 128.

100 The ends of the wrapper having been shaped by closing the preliminary folders, the dies swing into open position and the split cups 50 close upon the released ends of the envelops axially, the cups 50 being so shaped (Figs. 6, 7 and 8) that in engaging 105 110 115 120 125 130

the preliminary folded envelop ends 129, they fold down one of the upstanding channel sides and allow the other to enter into an axial slot 140, provided as shown in Fig. 11. 5 While the cigar is still being held stationary in the turret, the cups 50 are then turned through one revolution, thereby allowing the flaps 129 protruding from the slots 140 to be laid down on the ends of the envelop previously folded by the entering cups, as shown in Fig. 12. Next, the tuckers 141 are pressed down through transverse slots 142 of the cups upon the rolled ends of the envelop to form tucks at the extreme ends of the envelop; 10 and taper-pointed reciprocatory plungers 51 are then pushed axially against the tucks, as shown in Fig. 13, thereby bending said tucks upwardly. The folders 141 are then lifted into their raised position, leaving the upturned tucks upon the taper-points of the plungers 51 (Fig. 14), the latter then being further advanced into the position shown in Fig. 15, to fold the flaps 129 down tightly against the cigar. Finally, the rotatory cups 15 50 are turned through another revolution (Fig. 15), thereby causing the face 143 of their transverse slots 142 to smooth out the folds and give the envelop the appearance shown in Fig. 16.

30 The cups 50 are mounted in the ends of the hollow shafts 49 provided with long keyways 144 and with shoulders 145 between which and the end collars 146, are mounted the sleeve blocks 147 slidable upon and between the 35 guide bars 148 attached to the frame 20. The blocks 147 carry cam rollers 149 engaging cams 150 on the shaft 26, and also support the shafts 151 (Figs. 1^a and 3) upon which are mounted the tuckers 141. In a slot provided in the brackets 41, are mounted, upon the hollow shafts 49, pinions 152 engaging interrupted gears 153 on the shaft 26, the 40 gears 153 on a portion of their perimeter having two sets of teeth separated by a depression in such manner that in turning each set of teeth on 153 causes the pinions 152 to make one revolution, between which it remains stationary during the passage of the intermediate depression and also during the passage 45 of the remaining portion of the perimeter which is likewise depressed. The pinions 152 carry keys 154 in engagement with the long keyways 144 in the shafts 49, the gears 153 being so set that the blank portions of their perimeters lock the pinions 152 while the cups 50 are out of engagement, and that the toothed portions turn the pinions while the cups are in engagement with the envelop ends. The cams 150 are timed to reciprocate 50 the cups in and out of engagement with the envelop ends at the proper moment.

60 The reciprocating plungers 51 are slidably mounted within the hollow shafts 49 and are controlled by blocks 155 attached to their ends 65 and carrying cam rollers 156 engaging sec-

ond tracks in the cams 150. The blocks 155 are fitted between and slide upon the guide bars 148, thereby preventing the plungers from turning.

70 The tuckers 141, which move with the shafts 49 and are at all times in register with the transverse slots 142 of the cups 50, are actuated at the proper time by gear segments 157 (Figs. 1^a and 3) mounted on shafts 151 within the pinion slots of the brackets 41. The segments 157 mesh with segments 158 on a shaft 159 which is supported by the brackets 41 and carries a slotted crank 160. With the slot in the crank 160 there engages a pin on a cam lever 161 pivoted on the stud 162 in the frame 20 and carrying the roller 163 engaging the cam track in the gear 46 on the shaft 24.

80 The enveloping of the cigar having been completed, the turret advances to its discharging station in which the arm holding the enveloped cigar 164 is again horizontal but points in the opposite direction from its assembly position. As the turret arm approaches the discharging station, the lever 114 controlled by the cam 115 actuates the oscillating cam 113 raising its roller 112 and thereby opening its clamp 86, so that the yielding base 87 thus released will push the cigar 164 out of the turret and into the carrier 165. Simultaneously, the ejector arms 166, which are loosely mounted on the shaft 33 and which are connected by a rod 167 and one of which carries a small pinion 168, are actuated through a segment 169 by a cam lever 170 fulcrumed on the shaft 35 and having a roller 171 in engagement with the cam 115.

85 The cigar 164 having been pushed into the carrier 165, both the ejector 166 and the carrier 165 turn through one quarter of a revolution and deposit the enveloped cigar upon the delivery table 172.

90 The carrier 165 is mounted on the shaft 33 which has a pinion 173 meshing with a gear segment 174 on the shaft 32 which is controlled by a cam lever 175 having a roller 176 in engagement with a cam 177 on the shaft 25.

95 The cigars delivered upon the table 172 are advanced step by step to make room for more by fingers 178 of bars 179 which are pivoted to cranks 180 mounted on the fulcrum shafts 32 and 36 respectively, the shaft 36 carrying the gear segment 181 which is in mesh with the segment 182 forming the third arm of the 3-arm lever actuated from the cam 69.

100 The machine is started and stopped by releasing or engaging a pin 183 of the rod 184 (Fig. 3) which actuates the shift lever 185 fulcrumed on the stud 186 carried by a bracket 187 attached to the frame 20 of the machine. The rod 184 passes through holes provided for this purpose in the uprights of the frame 20, and when turning it to release the pin 183, the spring 188 surrounding the shaft 130

pushes the movable member of the clutch 43 into engagement.

In view of the foregoing, a detailed description of the operation of the machine is deemed to be unnecessary and is therefore omitted in the interest of brevity.

What is claimed is:

1. A cigar enveloping machine, comprising a traveling assemblage receiver having separated assembling and sealing and discharging stations, means for assembling a cigar and an envelop in said receiver, means for partially enveloping the cigar at the assembling station, means for completing envelopment of the cigar between the assembling and sealing stations, means for closing by different folds the ends of the envelop at the sealing station, and means for discharging the sealed cigar at the discharging station. 70
2. A cigar enveloping machine, comprising a series of traveling assemblage receivers having separated assembling and sealing and discharging stations, means for assembling cigars and envelops in said receivers, means for partially enveloping cigars at the assembling station, means for completing envelopment of the cigars between the assembling and sealing stations, means for closing by different folds the ends of the envelops at the sealing station, means for discharging sealed cigars at the discharging station in the same arrangement in which they are received at the assembling station, and actuating means for simultaneously operating said assembling means, said sealing means, and said discharging means at their respective stations. 80
3. A cigar enveloping machine, comprising a traveling assemblage receiver having separated assembling and sealing and discharging stations, means for assembling a cigar and an envelop in said receiver, means for partially enveloping the cigar at the assembling station, means for completing envelopment of the cigar between the assembling and sealing stations, means for closing by different folds the ends of the envelop at the sealing station, means for discharging the sealed cigar at the discharging station, and means for feeding box rows of cigars to the assembling station. 90
4. A cigar enveloping machine, comprising a traveling assemblage receiver having separated assembling and sealing and discharging stations, means for assembling a cigar and an envelop in said receiver, means for partially enveloping the cigar at the assembling station, means for completing envelopment of the cigar between the assembling and sealing stations, means for closing by different folds the ends of the envelop at the sealing station, and means for discharging the sealed cigar at the discharging station, said assembling means including means for turning the cigar 90 degrees and moving it with its envelop into said receiver at the assembling station. 100
5. A cigar enveloping machine, comprising a traveling assemblage receiver having separated assembling and sealing and discharging stations, means for assembling a cigar and an envelop in said receiver, means for partially enveloping the cigar at the assembling station, means for completing envelopment of the cigar between the assembling and sealing stations, means for closing by different folds the ends of the envelop at the sealing station, and means for discharging the sealed cigar at the discharging station, said partially enveloping means including means for folding the underlap edge of the envelop on the cigar in the receiver at the assembling station. 110
6. A cigar enveloping machine, comprising a traveling assemblage receiver having separated assembling and sealing and discharging stations, means for assembling a cigar and an envelop in said receiver, means for partially enveloping the cigar at the assembling station, means for completing envelopment of the cigar between the assembling and sealing stations, means for closing by different folds the ends of the envelop at the sealing station, and means for discharging the sealed cigar at the discharging station, said completing means including means for folding the overlap edge of the envelop on the cigar between the assembling and sealing stations. 120
7. A cigar enveloping machine, comprising a traveling assemblage receiver having separated assembling and sealing and discharging stations, means for assembling a cigar and an envelope in said receiver, means for partially enveloping the cigar at the assembling station, means for completing envelopment of the cigar between the assembling and sealing stations, means for closing by different folds the ends of the envelop at the sealing station, and means for discharging the sealed cigar at the discharging station, said closing means including cooperating oscillatory and rotary and reciprocatory folding devices simultaneously operating on both ends of the envelop at the sealing station. 130
8. A cigar enveloping machine, comprising a traveling assemblage receiver having separated assembling and sealing and discharging stations, means for assembling a cigar and an envelop in said receiver, means for partially enveloping the cigar at the assembling station, means for completing envelopment of the cigar between the assembling and sealing stations, means for closing by different folds the ends of the envelop at the sealing station, and means for discharging the sealed cigar at the discharging station, said discharging means including means for turning the cigar 90 degrees while discharging it from said receiver at the discharging station. 140
9. Means for assembling cigars and envelops therefor, comprising an assemblage

receiver, means for feeding an envelop across the front of said receiver, concentric quarter-circular guides for turning cigars, and a plunger for moving a cigar forward between said guides and for moving the turned cigar with its envelop into said receiver.

10. Means for closing the ends of envelops enclosing cigars, comprising an assemblage receiver supporting an enveloped cigar, and different cooperating oscillatory and rotatory and reciprocatory folding devices simultaneously operating on both ends of an envelop enclosing a cigar in said receiver to fold said ends by different folds on the cigar.

15. Means for closing the ends of envelops enclosing cigars, comprising an assemblage receiver supporting an enveloped cigar, means for giving channel form to the ends of an envelop enclosing a cigar in said receiver, and cooperating oscillatory and rotatory and reciprocatory folding devices thereafter acting on said ends to fold them by different folds.

20. Means for closing the ends of envelops enclosing cigars, comprising an assemblage receiver supporting an enveloped cigar, preliminary folders acting on the ends of an envelop enclosing a cigar in said receiver, split cups, means for moving said cups in and out of engagement with the preliminarily folded ends of the envelop, means for rotating said cups when in engagement with the preliminarily folded ends, means for forming tucks on the ends of the envelops, and means for backwardly turning the tucks to fold them on the cigar.

25. Means for closing the ends of envelops enclosing cigars, comprising an assemblage receiver supporting an enveloped cigar, means for giving channel form to the ends of an envelop enclosing a cigar in said receiver, split cups, means for moving said cups in and out of engagement with the formed ends of the envelop, means for rotating said cups when in engagement with the ends of the envelop, oscillatory tuckers cooperating with said cups to form tucks on the ends of the envelops, and plungers axially reciprocating in said cups to backwardly fold the tucks on the cigar.

30. Means for discharging cigars from enveloping means, comprising an oscillatory carrier for the cigars, an oscillatory ejector for transferring cigars from the enveloping means to said carrier, and cam-actuated gearing for producing the oscillatory movements of said carrier and said ejector.

35. Machine for wrapping cigars and other elongated bodies, comprising in combination, means for enclosing the body in a tubular wrapper the ends of which wrapper project beyond the body, means for holding the body thus enclosed in the tubular wrapper, male and female dies located at opposite ends of the

tubular wrapper, means for approaching the male and female dies towards each other transversely of the body, means for distancing such male and female dies after the under ends of the wrapper have been bent upwards to form two side ears, means for turning inwardly one side ear fold of the two side ear folds formed by the dies at each end of the body, means for turning inwardly the other side ear fold in the opposite direction to overlap the first side ear fold, and means for turning down the central projecting ear fold formed at each end of the wrapper by the turning in of the side ear folds.

40. Machine for wrapping cigars and other elongated bodies, comprising in combination, means for enclosing the body in a tubular wrapper the ends of which wrapper project beyond the body, means for holding the body thus enclosed in the tubular wrapper, male and female dies located at opposite ends of the tubular wrapper, means for approaching the male and female dies towards each other transversely of the body, means for distancing such male and female dies after the under ends of the wrapper have been bent upwards to form two side ears, means for turning inwardly one side ear fold of the two side ear folds formed by the dies at each end of the body, means for turning inwardly the other side ear fold in the opposite direction to overlap the first side ear fold, means for supporting the base of the central projecting ear fold formed at each end of the wrapper by the turning in of the side ear folds, and means for turning down the said central projecting ear folds.

45. A cigar enveloping machine, comprising a traveling assemblage receiver having separated assembling sealing and discharging stations, means for assembling a cigar and an envelop in said receiver, means for partially enveloping the cigar at the assembling station, means for completing envelopment of the cigar between the assembling and sealing stations, means for closing the ends of the envelop at the sealing station, and means for discharging the sealed cigar at the discharging station, said closing means comprising devices for folding in opposite side portions of the envelop along the tapering ends of the cigar, and means for forming the projecting ends into flat tongues and transversely folding said tongues close to the cigar ends.

50. In a cigar enveloping machine, mechanism for closing the ends of an envelop encircling a cigar and projecting beyond the ends thereof, comprising means for folding opposite side portions of the envelop along the tapering ends of the cigar, means having a pair of transversely extending parallel surfaces and mechanism for bringing said surfaces together on opposite sides of the pro-

jecting material to pinch together a portion thereof beyond the ends of the cigar in the direction of its length, and means for transversely folding the pinched portion.

5 19. Means for closing the end of an envelop enclosing an article, comprising a support for the enveloped article, and different cooperating oscillatory and rotatory and reciprocatory folding devices operating on the end of 10 the envelop enclosing the article in said support to fold said end by different folds on the article.

15 20. Means for closing the ends of envelops enclosing cigars, comprising a support for the enveloped cigar, means for giving channel form to the ends of the envelop enclosing the cigar in said support, and mechanism thereafter acting on said ends to fold them on the cigar between its ends.

20 21. In a cigar enveloping machine, comprising a traveling assemblage receiver having separated assembling and sealing and discharging stations, means for assembling a cigar and an envelop in said receiver, means 25 for partially enveloping the cigar at the assembling station, means for completing envelopment of the cigar between the assembling and sealing station, means for closing by different folds the ends of the envelop at 30 the sealing station, means for discharging the sealed cigar at the discharging station, and means for feeding box rows of cigars to the assembling station, said means for feeding boxrows of cigars including a shaft, sprockets 35 on said shaft, conveyor chains running over said sprockets and adapted to feed box rows of cigars, a ratchet on said shaft, a lever loosely mounted on said shaft, a spring holding said lever in rearward tension, cam means 40 for intermittently actuating said lever in a forward direction, whereby to advance said pawl to intermittently rotate said shaft, and a finger connected to and actuated from said 45 shaft to engage with the leading cigar of each row at each back stroke of said pawl.

22. Means for feeding box rows of cigars, comprising a shaft, sprockets on said shaft, conveyor chains running over said sprockets 50 and adapted to feed box rows of cigars, a ratchet on said shaft, a lever loosely mounted on said shaft, a spring holding said lever in rearward tension, cam means for intermittently actuating said lever in a forward direction, whereby to advance said pawl to intermittently rotate said shaft, and a finger connected to and actuated from said shaft to engage with the leading cigar of each row at 55 each back stroke of said pawl.

60 23. Means for feeding box rows of cigars, comprising a shaft, sprockets on said shaft, conveyors running over said sprockets and adapted to feed box rows of cigars, mechanism for intermittently rotating said shaft, 65

and a finger connected to and actuated from said shaft for intermittently engaging the leading cigar of each row.

In testimony whereof, I have signed my name to this specification.

HENRY H. WHEELER.
